UNITED STATES PATENT OFFICE.

ARTHUR J. DAANE, OF CHICAGO, ILLINOIS.

VIBRATOR FOR PRINTING PRESSES.

Application filed October 13, 1921. Serial No. 507,489.

To all whom it may concern:

Be it known that I, ARTHUR J. DAANE, a citizen of the United States, residing at Chicago, in the county of Cook and State 5 of Illinois, have invented a certain new and useful Improvement in Vibrators for Printing Presses, of which the following is a full, clear, concise, and exact description, reference being had to the accompanying 10 drawings, forming a part of this specification.

The invention relates to ink distributing rollers for printing presses, and primarily to a means for removably attaching said 15 roller to the frame of a printing press without necessitating any change to be made to the press by either the addition to or subtraction of parts from the press to permit 20 of the association or removal of the ink distributing roller.

The invention has as its prime object the provision of a structure capable of performing the above advantages which is adapted for association and removal from 25 what is generally known as the lower inking roller of a printing press of that type in which the inking rollers are attached to one end of a swinging frame which when actuated causes the inking rollers to travel 30 or travel over the ink platen and the type. This lower inking roller is journaled at its opposite ends in a hooked shaped portion of a yieldable member which is carried by this swinging frame, and it is an object 35 to produce a construction which is capable of removable association with this hook shaped part.

In addition to the above it is a further 40 object to provide a structure which is capable of association with this part of the press, and which is also capable of accommodating itself to various shaped surfaces over which the inking rollers ride during their travel to and from the platen and type, 45 and in addition will insure a close connection between the inking rollers and distributing rollers and compensate for variations in the diameters or surfaces of the inking rollers.

It is an additional object of the invention 50 to provide a construction which will securely hold the ink distributing roller with respect to the swinging frame, yet will permit of the ready dissociation and connection of the parts when it is desired.

The device forming the basis of the ap-

plication is designed to be arranged at the opposite ends of an ink distributing roller and in its present form consists of two parts 60 hingedly connected together. One of these parts is constructed to yieldably hold the shaft of the ink distributing roller and the other is designed to be removably attached to the hooked end of the swinging inking roller frame. This last-mentioned portion 65 is formed to produce what might be termed a stirrup, into which the hooked end of the inking roller frame is arranged. As before stated, the ink distributing roller is arranged to yield to accommodate itself to 70 various contingencies. To permit this a spring element is employed which assists in maintaining the associated relation of the stirrup and hooked portion of the inking rollers, and also allows the ready disconnection of the ink distributing roller 75 and the hooked end of the inking roller support. When the distributing roller is arranged for use, it is positioned between the lower inking roller and the adjacent 80 roller of the upper inking rollers.

The invention will be explained in conjunction with the accompanying drawings which disclose various forms of which the invention is susceptible, it being understood 85 however, that the means for accomplishing the invention is not limited to that shown, the scope of the invention being defined by the appended claims forming a part herefor.

In the drawings Figure 1 is a side elevation of a portion of a printing press having the invention applied thereto.

Figure 2 is a side elevation of the device 95 for removably attaching the inking roller to the press.

Figure 3 is an end view of the device shown in Figure 2.

Figures 4 and 5 are end and front views 100 of a modified structure which may be resorted to.

The structure illustrated in the drawings for accomplishing the invention consists of a member 10 and a member 11, which are hingedly secured together at 12, it being 105 understood that the opposite ends of the distributing roller 13 are provided with a device composed of these elements and as they are substantially identical with each other an explanation of the structure of one will suffice for an understanding of both. These elements 10 and 11 may be 110

either stamped from a piece of sheet metal or cast as desired. The member 10 may be termed a stirrup and is shaped to readily engage the hooked end 14 of the swinging frame 15 to which the inking rollers 16, 17 and 18 are secured and which in one form of printing press travels over the platen 19 and the type, upon the actuation of the swinging frame.

10 The member 10 or stirrup is formed to provide the channel shaped portion 20, which is thus constructed to receive the end 21 of the hook 14. The walls 22 and 23 of the channeled portion engage the inner and 15 outer faces of the hooked end 21 and hold this portion of the stirrup against movement. The material of which the wall 22 is formed extends downwardly and provides the wall 24 which is substantially 20 parallel to the walls 22 and 23, it being connected to the wall 22 by means of the connecting portions 25-25. This wall 24 has an inwardly projecting ledge 26 which projects inwardly beyond the portions 25-25. This wall and the wall 24 are provided to engage the portion 27 formed by the juncture of the shaft 28 and the hook portion. One of the walls 25 has an arm 29 extending therefrom which is integral 30 therewith, to which the member generally designated 11 is pivotally secured at the pivot 12. This arm acts as a lever and maintains the walls 26 and 27 and the channel shaped portion 20 in contact with those 35 portions of the hook which they respectively engage when these portions of the device are arranged for cooperation with the hook and the ink distributing roller is arranged for cooperation with the inking 40 rollers of the press.

The member 11 which is pivotally connected to the lever 29 is formed to produce the portion 30 and the right angled portion 31. The portion 30 is provided with 45 a slotted aperture 32 provided for the reception of the end of the shaft 33 upon which the ink distributing roller 13 is arranged for reciprocation. This slot permits the shaft 33 to reciprocate with relation to the bracket 11 so as to allow the ink distributing roller to accommodate itself to the variously shaped surfaces over which it travels with the inking rollers to and from the platen of the press and the type, and also 50 allows the ink distributing roller to be cooperatively arranged and removed relatively to the inking rollers of the press when it is desired to attach and remove the device with respect to the press. The portion 55 31 of the bracket 11 has a housing 34^a secured to it within which spring pressed plunger 35 is mounted for reciprocation, the plunger being secured to the shaft 33, and being formed with a shoulder 36 with which 60 one end of the coil spring 37 is in engage- 65

ment, the opposite end of the spring being in contact with the end of the housing 34^a. This allows the shaft 33 to reciprocate in the slot 32, yet maintains the ink distributing roller in contact with the inking 70 rollers and also allows the shaft and ink distributing roller to be positioned to and removed from cooperation with the press.

The structure may be provided with a tensioning device to vary the pressure 75 exerted by the ink distributing roller. To accomplish this the housing 34^a will be provided with screw threads 38 which are in threaded engagement with the portion 31 of the bracket, and thus by rotating the housing by means of the knurled head 39 the tension of the coiled spring within the housing will be varied. A set nut 40 may be utilized to hold the housing in its adjusted 80 position.

If desired the stirrup portion 10 may be provided with an inwardly projecting pin or extension 41 which engages the wall 42 of the hook and assists to hold the stirrup with relation to the hook. To apply the device to the inking rollers of the press and the hook 14 the ink distributing roller 13 is placed in position relatively to the inking rollers of the press and the stirrup portion generally designated 10 is passed over the uppermost end of the hook. The member 11 is then depressed which brings the channeled portion 20 below the part 21 of the hook. Upon the release of the pressure upon the member 11 the spring in the 100 housing 34^a is permitted to act which imparts an upward movement to the arm or lever 29, bringing the portions 24 and 26 into contact with the part 27 formed by the juncture of the shaft 28 and the hook. To 105 remove the device a downward pressure will again be applied to the member 11. This will allow the portion 10 to drop away from the hook so that it will clear it and allow the entire structure to be lifted away from 110 the press.

In Fig. 4 a modified structure is illustrated which accomplishes the same function as the structure shown in the preceding figures, differing in structure however, in the employment of a portion which is movable laterally relatively to other portions of the device towards and away from the hook to affect a connection of the device and the hook, this movable portion having means 115 for releasably engaging certain portions of the hook.

In this structure a member 11^a is employed which may be constructed and provided with means such as the housing, 125 spring, etc., this portion also being designed to accommodate the end of the shaft in a manner similar to that previously described. The other portion as 10^a is hinged or pivoted to the member 11^a at 45. This 130

member is provided with a pin 46 which is arranged in the housing 47, the latter of which extends from the member 11^a, and is arranged concentrically with the pivot of these members 10^a and 11^a, the housing and pin providing a pivot for the members 10^a and 11^a. The pin is provided with an enlargement 48 and a coiled spring is arranged upon the pin and this spring reacts between the head of the pin and the member 11^a. This allows the member 10^a to be moved outwardly with respect to the member 11^a, yet will retain this member in cooperative relation to the hook of the printing press roller frame. This member 10^a is further provided with the inwardly extending pins 48^a and 49, which are moved with the portion 10^a when the device is to be applied and removed relatively to the press. The pin 48 is preferably square so that it will fit the corner 50 formed at the juncture of the hook and shaft. The pin 49 engages the inner face of the hook as shown and cooperates with the pin 48 and the coiled spring to releasably hold the member 10^a in cooperative relation to the swinging frame of the press.

It is evident that all that is required to connect and disconnect this structure is to move the member 10^a away from the hook which will release this structure from the hook.

From the foregoing description it is evident that simple and effective structures are procured whereby an ink distributing roller may be applied and removed from a printing press, the structures permitting of the association of the distributing roller and press without necessitating any changes to be made to the press to accomplish the desired end.

Having thus described the invention, what I claim and desire to secure by Letters Patent is:

1. In an ink distributing roller for printing presses the combination of a member for removably attaching said roller to the hooked end of a printing roller frame by being moved transversely to the axis of the roller and passed through the mouth of the opening of the hook, said member having means for engaging said hook, said means providing the means for releasably holding said member against separation from the hook when arranged in cooperative relation to the hook.

2. In an ink distributing roller for printing presses, the combination of a member adapted to be removably attached to the hooked end of a printing roller frame by being passed through the mouth of the opening, said member having portions which engage oppositely disposed portions of the opening of the hook.

3. In an ink distributing roller for print-

ing presses, the combination of a member adapted to be removably attached to the hooked end of a printing roller frame, said member having a portion which is passed into the mouth of the opening and into cooperative engagement with the hook, and another member pivotally connected to said first mentioned member, said last mentioned member having an ink distributing roller secured thereto and having means cooperating to hold said first mentioned member with relation to the hook.

4. In an ink distributing roller for printing presses, the combination of a member adapted to be removably attached to the hooked end of a printing roller frame, said member having a portion which is passed into the opening at the termination of the hook and into cooperative engagement with opposed portions of the material forming the opening of the hook, an ink distributing roller secured to said member and means whereby said member may move with relation to said roller.

5. In an ink distributing roller for printing presses, the combination of a member adapted to be removably attached to the hooked end of a printing roller frame, said member having a portion which is passed into the opening at the termination of the hook and into cooperative engagement with the hook, another member pivotally connected to said first mentioned member, said last mentioned member having an ink distributing roller secured thereto, and a connection between said last mentioned member and the distributing roller whereby said roller may move transverse to the axis of the roller and with respect to the hook.

6. In an ink distributing roller for printing presses, the combination of a member adapted to be removably attached to the hooked end of a printing roller frame, said member having a portion which is passed into the opening at the termination of the hook and into cooperative engagement with the hook, and resilient means for maintaining said member in contact with the hook.

7. In an ink distributing roller for printing presses, the combination of a member adapted to be removably attached to the hooked end of a printing roller frame, said member having a portion which is passed into the opening at the termination of the hook and into cooperative engagement with the hook, an ink distributing roller secured to said member, means whereby said member may be moved with relation to said roller, and yieldable means for maintaining said member in associated relation with the hook.

8. In an ink distributing roller for printing presses, the combination of a member adapted to be removably attached to the hooked end of a printing roller frame, said member having a portion which is passed

into the opening at the termination of the hook and into cooperative engagement with the hook, and resilient means for releasably maintaining said member in contact with the hook.

9. In a device of the class described, the combination of a pair of members pivotally connected together, one of said members having the shaft of an ink distributing roller associated therewith, the other member having means for cooperatively engaging an inking roller frame of a printing press and means for holding said member in associated relation to said frame of the printing press said means providing means for holding the distributing roller in contract with an ink roller of said press.

10. In a device of the class described, the combination of a pair of members pivotally connected together, one of said members having the shaft of an ink distributing roller associated therewith, the other member having means cooperatively engaging the hooked end of an inking roller frame of a printing press by movement thereof transversely to the axis of an ink roller with which the distributing roller co-operates.

11. In a device of the class described, the combination of a pair of members pivotally connected together, one of said members having an ink distributing roller secured thereto, the other member having a channeled portion for engagement with the hooked end of an inking roller frame of a printing press, said distributing roller being secured for reciprocation transversely to the axis of an inking roller carried by the inking roller frame and relatively to said member to which the inking roller is secured.

12. In a device of the class described, the combination of an element having an ink distributing roller secured thereto, a resilient tension member carried by said element, said element having a channeled portion for releasably engaging the hooked end of an inking roller frame of a printing press, said resilient tension member acting upon the roller to maintain said roller in contact with the inking rollers of the press and also acting upon said element having the distributing roller secured thereto to maintain said element in associated relation with the hooked end of said inking roller frame.

13. In a device of the class described, the combination of an element having an ink distributing roller attached thereto, and having means provided to engage the hooked end of an inking roller frame, said means including a portion which is inserted into the mouth of the opening and having oppositely extending members which engage the hook adjacent the opening.

14. In a device of the class described, the

combination of a pivoted element having an ink distributing roller attached thereto and having means provided to engage the hooked end of an inking roller frame, said means having means for engaging the opposite sides of the opening and having means extending in opposite directions from the openings.

15. In a device of the class described, the combination of a pair of members pivotally connected together, one of said members having the shaft of an ink distributing roller associated therewith, the other member having means for engaging a hooked portion of a printing roller frame by being moved transversely of the axis of an ink roller with which the ink distributing roller is adapted to be associated and being passed through the mouth of the opening of said hook shaped portion.

16. In a device of the character described, the combination of an ink distributing roller, a member to which said roller is connected, said member having a channel shaped portion provided to receive an end of a hook shaped portion of an inking roller frame of a printing press and having a portion extending in a direction opposite to the channel shaped portion, said last mentioned portion being arranged adjacent the channel shaped portion.

17. In a device of the character described, the combination of an ink distributing roller, a member to which said roller is connected, said distributing roller being reciprocable relatively to said member, a second member, a pivotal connection between said members, said second mentioned member having a channel shaped portion for receiving an end of a hooked shaped portion of an inking roller frame of a printing press and having a portion arranged adjacent the channel shaped portion and extending in the opposite direction.

18. In a device of the character described, the combination of an ink distributing roller, a member to which said roller is connected, said distributing roller being reciprocable relatively to said member, a second member, a pivotal connection between said members, said second mentioned member having a channel shaped portion for receiving an end of a hooked shaped portion of an inking roller frame of a printing press and having a portion arranged adjacent the channel shaped portion and extending in the opposite direction, said channel shaped portion and second mentioned portion being extended laterally relatively to the second mentioned member.

In witness whereof, I hereunto subscribe my name this 10th day of October A. D. 1921.

ARTHUR J. DAANE.
